Primary Examiner — Christy Nemeth(74) *Attorney, Agent, or Firm* — Novick, Kim & Lee,
PLLC; Jae Youn Kim; Hyun Woo Shin**CLAIM**

We claim, the ornamental design for a portable auxiliary battery, as shown and described.

DESCRIPTION

FIG. 1 is a perspective view of a portable auxiliary battery, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dash broken lines in the drawings show portions of the portable auxiliary battery which form no part of the claimed design. The dot-dash broken lines in the drawings represent boundaries which form no part of the claimed design.

1 Claim, 4 Drawing Sheets(56)
